UNITED STATES PATENT OFFICE

LOUIS FRED HAGEMANN, OF NIAGARA FALLS, NEW YORK, ASSIGNOR TO AMERICAN SALES BOOK COMPANY, LIMITED, OF TORONTO, CANADA, A CORPORATION OF ONTARIO, CANADA

PAPER ALIGNER FOR BILLING MACHINES

Application filed June 17, 1926, Serial No. 116,593. Renewed January 12, 1929.

This invention relates to billing or similar machines and more particularly in some of its details, it relates to improvements in mechanisms for adjusting and aligning the paper record strips used in such machines so as to bring said strips in correct position for the reception of an inscription, and furthermore to tension the strips for similar purposes.

It is the general object of the invention to provide an improved practical mechanism for positioning and aligning one or a plurality of superposed record strips or sheets to bring them into correct inscription receiving position on a support or platen, and for relatively 15 aligning the strips where a plurality of superposed strips are employed so as to bring the strips into correct superposed registry.

It is a further object of the invention to provide, in a machine of the class mentioned, an improved strip aligning member to which is imparted a compound motion whereby entry into aligning apertures formed in the strip or strips is facilitated, and furthermore to provide means to positively direct said aligning member in its aperture entering movement.

A further object is to provide, in a machine of the class mentioned, an improved strip aligning mechanism to positively align and 30 position the strip or strips in inscription receiving position and to positively tension said strips and clamp them in aligning position.

A further object is to provide, in a machine of the class mentioned, an improved manually 35 operable oscillatable strip engaging member, engageable with the strip or strips to positively adjust them into aligned position.

Another object is to provide, for machines of the class mentioned, an improved aligning mechanism adapted to engage one or a plurality of superposed record strips at parts spaced longitudinally thereof and to provide an improved operating mechanism to manually move one of the engaging mechanisms 40 longitudinally with reference to the other, so as to positively move the strips into correct position.

Still another object is to provide an improved mechanism of the class mentioned 50 which is simple in construction, positive and

effective in operation, and capable of simple and quick installation on billing or like recording machines of existing construction.

Other objects will be in part pointed out in the following detailed description of an 55 illustrative but preferred embodiment of the invention, and will be in part obvious in connection therewith.

The invention accordingly comprises the features of construction, combinations of elements, and arrangement of parts, which will be exemplified in the construction hereinafter set forth and the scope of the application of which will be indicated in the claims.

For a more complete disclosure of the nature and objects of the invention, reference is had to the following detailed description, and to the accompanying drawings in which:

Figure 1 is a plan view of a billing machine of the flat platen type embodying the 70 invention, parts being broken away or removed to facilitate disclosure;

Fig. 2 is a fragmentary vertical longitudinal section taken substantially on the line 2—2 of Fig. 1;

Figs. 3, 4 and 5 are detail views of one of the strip aligning pins, showing it in different successive positions in its strip aligning movement;

Fig. 6 is a view similar to Fig. 4, but showing the aligning pin in its movement of retraction from engagement with a record strip aperture, and the action of stripping the strip from the pin, and

Fig. 7 is a fragmentary plan of one of the 85 record strips.

The improved aligning and tensioning mechanism may be embodied in writing or like machines of different character but it is particularly adapted for application to 90 billing machines and may be applied as an attachment to billing machines of existing construction.

Referring to the drawings for a detailed description of the embodiment of the invention there shown, it will be observed that the improved aligning mechanism is applied to a 95 billing machine of the flat platen type over which the writing machine proper travels 100

upon supporting rails in order to effect line spacing.

The supporting frame for the machine may be of any preferred form, the showing of the drawing being somewhat diagrammatic and fragmentary for convenience of illustration. The main supporting framework or base 10 carrying the operative mechanisms of the machine may be supported in any desired manner as by a pedestal or other form of support (not shown). The framework 11 for supporting the track and the record sheets to be written upon may be supported upon the base 10, and includes two parallel longitudinal side rails or bars 12 connected by transverse frame members or cross bars 13. The typewriting machine employed for writing upon the record strips is diagrammatically shown in dot and dash outline at 14 and is mounted upon the longitudinal side rails for movement back and forth thereon over a flat writing platen 15 which supports the record sheets or strips S in flat smooth position for receiving the impact of the type. As will be understood by those familiar with this art, the general arrangement of the record strips and typewriting machine is such as to permit the type to strike upon different parts of the record strips S to impart printed impressions thereto, whereby blank bill forms or like forms upon the strips may be filled in with appropriate data. As it is usually desired to make more than one copy, a plurality of superposed record strips may be employed as shown in the drawing, carbon sheets or similar transfer material being interposed between the adjacent superposed sheets over the platen. If carbon paper is used to transfer the records, the supply thereof may be supported adjacent the platen in any preferred known manner. As many record strips S may be superposed, one on another as desired to provide the required number of copies.

The supply of blank record strips is preferably arranged in the form of a zigzag supply pack or pad S' which may be supported and housed upon or adjacent to the machine in any convenient manner. Each of the record strips may be provided with apertures S² therein which are preferably arranged in two longitudinal series on each strip providing pairs of apertures disposed upon transverse lines of the strips as shown in the drawing. These apertures are utilized for cooperation with strip aligning and tensioning mechanism described below, the pairs of transversely disposed apertures respectively bearing a definite relation to blank forms which may be printed in a longitudinal series upon each of the strips. Also it is desirable that adjacent blank forms on each of the strips be separated by transverse perforated or similarly weakened lines, thus dividing each of the strips into a series of form leaves. These

weakened transverse lines aid in severance of the form leaves from the strips after a record has been entered thereon.

In order to retain the record strips in correct position on the platen for reception of an entry or inscription thereon, and to assist in effecting alignment of the strips with reference to each other and to the writing platen, a clamp or similar holding means is provided in the vicinity of the platen. This strip retaining means may be of different preferred forms, that shown being in the form of transverse clamping bar 16 positioned to rest against a cross plate 17 mounted in forwardly inclined position at the front of the machine upon one of the cross frame members 18. This cross plate is removably clamped in position by means of clamps 18 engaging lugs 19 upon the cross plate and appropriate lugs on the frame of the machine as shown. The cross plate 17 is provided with a pair of upstanding pins or posts 20 preferably flattened or elliptical in cross-section and positioned to enter the apertures formed in the record strips S, and apertures 21 of the clamping bar 16. The major axes of the pins 20 are aligned transversely of the frame, and the longitudinally disposed minor axes are considerably shorter than the diameters of the apertures 21, permitting longitudinal adjustment of the cross-plate 17 relatively to the clamping bar 16. Also the minor axes of the elliptical pins 20 are considerably shorter than the diameter of the strip apertures so as to permit longitudinal adjustment of the strips when impaled by the aligning pins 20. In the illustrative embodiment disclosed, the pins 20 are rigid and stationary with reference to the cross bar 17 and with reference to the frame of the machine. The clamping bar 16 serves as a severing edge at the forward part thereof for tearing off the form sheets from the supply strips, and the pin supporting cross plate 17 underlying the clamping bar is cut away at its forward edge to provide a recess to facilitate grasping of the forward edges of the strip.

Movement of the clamping bar 16 to and away from the cross plate 17 to grip and release the underlying record strips may be provided for as shown in the drawing by means of a system of levers controlled by a rod or link 23 connected to a manual operating member, as a pedal 24 pivoted to a supporting standard or column 25 depending from and mounted upon the base plate 10. As shown the clamping bar 16 at its opposite ends is connected to and supported by levers 26 pivoted to the side rails 12 by means of a transverse rod 27 extending through the levers and attached at its opposite ends to the side rails. Each of the levers 26 is furthermore articulated to the adjacent side rail by means of a link 28 loosely pivoted to the lever 26 at 29, and pivoted to the adjacent

side rail at 30. The rock arms or levers 26 are biased to hold the clamping bar in gripping position by means of one or a plurality of tensioning springs 31 anchored to the frame and to the lugs 32 depending from the rock arms. A U-shaped operating lever or yoke 33 is pivoted through its opposite legs to the adjacent links 28 by means of a pivotal rod 34, the leg of the yoke extending beyond this pivotal rod to underlie and contact with the rod 27 which thus acts as an abutment or fulcrum for the lugs of the U-lever when it is rocked by the pedal to operate the clamping rod. The pedal rod 23 may be connected by means of a hook at its upper end to the U-lever 33. By means of this mounting for the clamping bar 26 and the operating connections therefor, it will be seen that depression of the pedal will raise the clamping bar to release its grip upon the strips, while the bar is returned to gripping position by operation of the springs 31 when pressure upon the pedal is released.

Positioned rearwardly of the platen is another strip engaging mechanism which is active in positioning and aligning the strips. This mechanism includes a rock shaft 35 extending transversely of the frame of the machine and connected to be rotated in strip aligning direction by raising of the pedal. These operating connections include a crank arm 36 secured to the rock shaft 35 and connected by a link 37 with one arm of a bell-crank lever 38 pivoted to a bracket 39 which may be detachably attached to one of the cross frame members 13. The opposite arm of the bell-crank lever 38 is positioned to lie in a notch or aperture 40 formed in a connecting bracket or link 41 which is clamped in position upon the bow of the U-shaped lever or yoke 33. The rod or link 37 is preferably connected to the crank 36 by means of a crank pin 42 rotatably mounted in an aperture in the crank and held therein by a cotter pin or similar securing means. The end of the operating link extends through an opening in the head 43 of the crank pin and is secured to the pin by nuts 44 on the link positioned at each side of the crank pin head so as to anchor the connecting link securely to the crank pin. At its opposite end the operating link 37 is securely connected to a crank pin 45 on the bell-crank lever 38, being similar to crank pin 42 and the link 55 being secured against longitudinal sliding movement through the crank pin by nuts 46 threaded on the link and positioned at both sides of the crank pin.

The rock shaft 35 is preferably mounted at its opposite ends in supporting plates or brackets 47 spaced apart so as to lie with their outer faces against the inner faces of the side bars 12. These supporting brackets are arranged to be clamped and supported in position on the machine frame by clamps 48 pref-

erably attached to the brackets and spanning the lower edges of the side rails and secured to said side rails by set screws or similar securing means. Secured also to the supporting brackets 47 and extending transversely of the machine frame are structural tie bars 49 and 50 which may also function as strip guiding and supporting rods, and an additional strip guiding and supporting rod 51 having edge guiding flanges 52 thereon for positioning the strips edgewise as they pass onto the bed of the machine from the supply pad. A unitary guiding and aligning member is thus provided by the bracket plates 47 and parts supported thereby which may readily be placed upon or removed from the billing machine. It will thus be seen that the entire strip aligning and tensioning attachment together with operating connections therefor may readily be applied to billing or like machines of existing construction with a minimum of labor and effort and without alteration or impairment to the machine construction and without interruption to the normal operative functions of the machine.

Rigid arms 53 are rigidly mounted upon the rock shaft 35 for rocking motion therewith, said arms extending above the shaft and being spaced apart a distance approximately equal to the transverse spacing of the strip aligning apertures. These rock arms together with the rock shaft constitute a rockable carrier for a pair of rigid strip engaging, strip aligning members or pins 54, each mounted on one of the arms 53 for projection into strip aperture engaging position and for retraction. In the embodiment shown, each of the projectable aligning pins pivoted to one of the carrier arms to effect the projection and retraction of the strip engaging part thereof, and is provided with a strip aperture engaging part or projection 55 which is preferably oblong in cross-section with the minor axis extending longitudinally of the machine frame, the forward strip engaging face thereof being rounded or cylindrical for contacting with the curved walls of the strip aligning apertures. Each aligning pin 54 is provided with a laterally projecting cam or lug 56 from which depends a stop lug 57 positioned for engagement with the rock arm to limit pivotal movement of the aligning pin in one direction. The rock arms are provided at their swinging ends with recesses for receiving the pivoted aligning pins and a spring pressed friction plug 58 is mounted upon the rock arm preferably at the bottom of said recess and positioned so that the outer end thereof is spring pressed into frictional contact with the lower cylindrical face of the aligning pin. This friction plug thus acts as a friction brake to restrain the pin in any position to which it may have been moved.

Positioned above the rockable carrier is a transverse tie rod 59 connected at opposite ends to the bracket plates 47 and providing a support for trips or trip lugs 60 which are positioned for contact with the pin operating lug 56, when the aligning pins are carried bodily by the carrier, so as to effect pivotal or rocking movement of the aligning pins. The outer ends of the trip lugs are also positioned for contacting with the adjacent faces of the pin projections 55 to rock the aligning pins in the opposite direction when the latter are moved by the carrier when swinging in the opposite direction. Rocking movement of the rock shaft 35 in either direction may be limited by suitable stops 61 mounted thereon and positioned to contact with the respective adjacent clamps 48.

The objects and nature of the invention having been set forth and an illustrative embodiment having been disclosed in detail, operation of the invention will now be understood, and for emphasis and clearness may be summarized as follows:

The pedal of the machine having been depressed to raise the clamping bar 16 and to move the aligning pins forwardly into strip disengaging position, the strip may then be threaded over the guide bar 51 into writing position over the platen, the forward ends of the strip being inserted under the clamping bar with the adjacent strip aligning apertures threaded over the stationary aligning pins 20. Pressure upon the pedal is then released whereupon the operating elements are positively returned to normal position under the influence of the spring 31 which is relatively heavy and of sufficient strength to positively force all the connecting operative elements into final position.

As the pedal is returned to normal position, the aligning pin carrier is positively rocked in a clockwise direction as viewed in Fig. 2, imparting movement of translation to the aligning pins 54, and as this movement continues the lugs or cams 56 contact with the trips 60 effecting rotary movement of the pins in a direction counter to the rotation of the carrier. A composite movement, that is movement of rotation and movement of translation, is thus imparted to the strip aligning pins, and the strip engaging projection 55 gradually swings into upright position, the end thereof wiping or sliding over the under face as the movement continues. Because of the composite movement of the aligning pins, entry of strip engaging projections into the apertures is facilitated, and to further facilitate this entry into the apertures, the operating connections are preferably positioned and proportioned so that the strip engaging ends of the pin projections are given a slight movement forwardly of the strip as they contact therewith, and are then moved rearwardly thereof. The effect of this

action is oscillatory movement of the strip engaging end of the pin projection longitudinally of the strip while in contact with the latter, the pin projection thus functioning as a sort of a feeler to find its way into the strip apertures. This feature is of special advantage and utility where a plurality of superposed strips are employed and the corresponding aligning apertures therein chance to be out of exact registry with each other. Due to this oscillatory action, the pin projection is enabled to thread its way into the apertures of the superposed strips. When the projections 55 reach substantially upright position, they are stopped there by contact of the stop lugs 57 with the adjacent faces of the rock arms. This stopping action occurs some time before the carrier reaches the rearward limit of its swinging movement so that, for the remainder of the movement of said carrier, the aligning pins move as a rigid unit therewith, the rounded or cylindrical surface of the pin projection being in engagement with the rearward walls of the aligning apertures so as to positively force the strips rearwardly into correct aligning position, and to tension and smooth them over the writing platen.

During the aligning action of the aligning pins 54 as described above, it will be understood that the strips are impaled at their forward extremities over the stationary strip aligning pins 20, but the strip aligning apertures being of greater diameter than the minor axes of the stationary aligning pins, relative longitudinal movement of the strips is permitted, while at the same time the forward ends of the strips are restrained within certain limits.

Also the operating connections are so proportioned and adjusted that the clamping bar 16 is set to grip the strips only after aligning action of the pins 54 is substantially completed, alignment of the strips being at that time completely effected. This function is accomplished in the embodiment of the invention shown by means of a connection between the upper or horizontal arm of the bell crank lever 38 and the bracket 41. Referring to Fig. 2, it will be seen that said upper arm and bracket are so proportioned and relatively positioned that the arm slides out of the slot 40 at the instant the aligning pins 55 have reached substantially final aligning position but prior to setting of the clamping bar 16 into a clamping position. The aligning pins then remain stationary in final aligning position while the clamp bar 16 descends to grip the strips thereunder. This permits free and unobstructed longitudinal aligning movement of the strips during the aligning action of the aligning pins 54. The clamping bar is set into clamping position upon the strips slightly after the aligning pins 54 reach their final rearward movement, where-

by the strips are gripped and positively held in correct position and smooth condition over the platen for entry of an inscription thereon. When the upper arm of the bell crank lever 38 slides from the slot 40 of the bracket 41 during ascent of the latter, the end of said arm contacts with the adjacent side of the cam lug 40^a which underlies the slot 40. This action prevents reverse movement of the bell crank lever thus locking the aligning pins in final aligning position. When the aligning pins are in final aligning position one of the stop lugs or pins 61 is substantially in contact with the adjacent bracket 48 as shown in Fig. 1 in full lines and Fig. 2 in dotted lines, so as to prevent the aligning pins from rearward movement beyond aligning position; this action also retains the upper bell crank lever arm in correct operative position relatively to the bracket 41. The other stop lug 20 61 as shown in full lines in Fig. 2, is positioned to contact with the adjacent bracket 48 substantially at the opposite limit of the rocking stroke of the carrier so as to limit carrier movement in the opposite direction.

When the entry is completed, the pedal is again depressed releasing the clamping bar and positively rocking the carrier in a counter clockwise direction as viewed in Fig. 2. As the pedal is depressed, the end of the upper bell crank lever arm first slides idly over the side of the cam lug 40^a and subsequently the lug 40^b of the bracket 41 contacts with said upper arm to positively rock the bell crank lever counter-clockwise and thereby through the operative connections described, positively rock the aligning pins and carrier therefor forwardly from strip aligning position. During this movement the end 40 of the upper arm of the bell crank lever is projected into the recesses 40 in a position to overlie the cam lug 40^a so as to be raised by the latter upon the return or upward stroke of the pedal. In this movement of the carrier, the trip 60 contacts with the adjacent faces of the pin projections 55 so as to positively rock the aligning pins in a clockwise direction and thus positively withdraw the pin projections from engagement with the strip aligning apertures. If for any reason the strip should stick or bind upon the pin projections, the engagement will be positively released by contact of the trips with the under side of the strips, that is, the trips 55 function as strippers to positively remove the strips from engagement with the aligning pins.

The pedal being depressed, the strips may then be manually pulled forwardly by grasping the forward ends thereof projecting into the aperture in the front edge of the cross plate 17, to bring fresh blank forms into position over the platen. The next successive strip aligning apertures are impaled upon 65 the aligning pins 20 and upon release of the

pressure upon the pedal, the cycle of operations of aligning the strips as above described is repeated. The projecting inscribed ends of the strips may then be severed across the forward edge of the clamping bar 16.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a strip aligning device for billing machines or the like, in combination, a pivoted strip aligning pin, a support for supporting said pin for bodily movement, and a trip member attached to the aligning device for automatically effecting pivotal movement of said aligning pin upon bodily movement thereof.

2. In a strip aligning device for billing machines or the like, in combination, a pair of pivoted strip aligning pins for entering aligning apertures in the strip, a support for supporting said aligning pins for swinging bodily movement, said pins being pivoted to said support, and a trip device attached to the aligning device for automatically effecting pivotal movement of said aligning pins so as to bring them into position for aligning engagement with the strip apertures.

3. In a strip aligning device for billing machines or the like, in combination, a pivoted strip aligning pin, a support for supporting said pin for bodily movement, a trip member attached to the aligning device for automatically effecting pivotal movement of said aligning pin upon bodily movement thereof, and a manual operating member having positive operating connections for positively effecting operative movement of said pin support.

4. In a strip aligning device for billing machines or the like, in combination, a pair of pivoted strip aligning pins for entering aligning apertures in the strip, a support for supporting said aligning pins for swinging bodily movement, said pins being pivoted to said support, a trip device attached to the aligning device for automatically effecting pivotal movement of said aligning pins so as to bring them into position for aligning engagement with the strip apertures, and a manual operating member having positive operating

connections for positively effecting operative swinging movement of said pin support.

5. In a strip aligning device for billing machines or the like, in combination, a pivoted strip aligning pin, a support for supporting said pin for bodily movement, a trip member attached to the aligning device for automatically effecting pivotal movement of said aligning pin upon bodily movement thereof, 10 and a strip restraining device spaced longitudinally from said aligning pin for restraining engagement with the strip during aligning operation of said strip aligning pin.

6. In a strip aligning device for billing machines or the like, in combination, a pair of projectable and retractable strip aligning pins for entering aligning apertures in the strip, a support for supporting said aligning pins for bodily movement, said pins being 15 mounted for projection and retraction upon said support, a trip device attached to the aligning device for automatically effecting projection of said aligning pins so as to bring them into position for aligning engagement 20 with the strip apertures upon bodily movement of said pins, a pair of strip restraining pins spaced longitudinally from said aligning pins, and a strip clamping bar mounted in proximity to said strip restraining pins.

30 7. In a strip aligning device for billing machines or the like, in combination, a pivoted strip aligning pin, a support for supporting said pin for bodily movement, a trip member attached to the aligning device for automatically 35 effecting pivotal movement of said aligning pin upon bodily movement thereof, a manual operating member having positive operating connections for positively effecting operative movement of said pin support, and a strip restraining device spaced longitudinally 40 from said aligning pin for restraining engagement with the strip during aligning operation of said strip aligning pin.

45 8. In a strip aligning device for billing machines or the like in combination, a pair of pivotal strip aligning pins for entering aligning apertures in the strip, a support for supporting said aligning pins for swinging bodily movement, said pins being pivoted to said 50 support, a trip device attached to the aligning device for automatically effecting pivotal movement of said aligning pins so as to bring them into position for aligning engagement 55 with the strip apertures, a manual operating member having positive operating connections for positively effecting operative swinging movement of said pin support, a pair of strip restraining pins spaced longitudinally 60 from said aligning pins for engagement with strip apertures during aligning operation of said strip aligning pins, and a strip clamping bar mounted in proximity of said strip restraining pins and operatively connected to 65 said manual operating member for operation

thereby in sequence with aligning operation of said strip aligning pin.

9. In a strip aligning device for billing machines or the like, in combination a pivoted strip aligning pin, a support for supporting said pin for bodily movement, a trip member attached to the aligning device for automatically effecting pivotal movement of said aligning pin upon bodily movement thereof, and a frictional restraining device for restraining pivotal movement of said pivoted aligning pin. 70 75

10. In a strip aligning device for billing machines or the like, in combination, a pivotal strip aligning pin mounted for movement of translation, and a frictional device for restraining said pin against pivotal movement. 80

11. In a strip aligning device for billing machines or the like, in combination, a pivoted strip aligning pin mounted for movement of translation, a frictional device for restraining said pin against pivotal movement, and a trip member cooperating to automatically effect pivotal movement of said aligning pin in opposite directions upon translatory movement thereof in different directions. 85 90

12. In a strip aligning device for billing machines or the like, in combination, a movable carrier, a strip aligning pin mounted upon said carrier for projection and retraction, and means independent of the strip and dependent upon movement of the carrier for automatically projecting and retracting said strip aligning pin to and from strip engaging position. 95 100

13. In a strip aligning device for billing machines or the like, in combination, a carrier mounted for swinging movement, a pair of strip aligning pins mounted upon said carrier for projection and retraction, and means independent of the strip and dependent upon movement of the carrier for automatically projecting and retracting said strip aligning pin to and from strip engaging position. 105

14. In a strip aligning device for billing machines or the like, in combination, a carrier mounted for swinging movement, a pair of strip aligning pins mounted upon said carrier for rotary movement into projected or retracted position, and automatic means dependent upon swinging movement of said carrier for rotating said pins in either direction in opposition to the direction of swinging movement of said carrier. 110 115

15. In a strip aligning device for billing machines or the like, in combination, a carrier mounted for reciprocatory movement, a strip engaging member mounted for translatory movement with said carrier and for projection thereon into position to engage apertures formed in the strip, operating mechanism for imparting reciprocatory movement to said carrier, and trip mechanism for positively and automatically projecting and re- 120 125 130

- tracting said strip engaging member upon reciprocal movement of said carrier.
16. In a strip aligning device for billing machines or the like, in combination, a carrier mounted for movement relatively to the strips to be aligned, a strip aligning member mounted upon said carrier and carried thereby into position for aligning engagement with apertures formed in the strips, and means for imparting an oscillatory movement to said strip aligning member as it is carried into position for engagement with said apertures. 10
17. In a strip aligning device for billing machines or the like, in combination, a carrier mounted for movement relatively to the strips to be aligned, a strip aligning member pivoted on said carrier and carried thereby into position for engagement in apertures formed in the strips, and a trip mechanism operating in conjunction with carrier movement to move said strip aligning member in opposite directions as it comes into contact with the strip face to facilitate entry into said apertures. 15
18. In a strip aligning device for billing machines or the like, in combination, a strip aligning member mounted for longitudinal movement relatively to the strip and engageable in aligning apertures formed in the strip, and a stripper for automatically forcing the strip and aligning member apart to free the engagement between said member and aperture. 20
19. In a strip aligning device, in combination, a swingably mounted carrier, a strip aligning pin mounted on said carrier so as to be moved into strip engaging or strip disengaging position and positive manual operating mechanism for positively swinging said carrier both in strip aligning and in reverse directions. 25
20. In a strip aligning device in combination, a clamp for clamping a strip against feeding movement, operating mechanism for said clamp, a swingably mounted carrier, a strip aligning pin mounted upon said carrier so as to be moved into strip engaging or strip disengaging position and operating connections controlled by said operating mechanism to positively swing said carrier in either direction and adapted to complete an aligning action of said pins prior to setting said clamp in clamping position. 30
21. In a strip aligning device in combination, a clamp for clamping a strip against feeding movement, operating mechanism for said clamp, a swingably mounted carrier, a strip aligning pin pivotally mounted on said carrier so as to be moved into strip engaging or strip disengaging position, a trip member for automatically moving said aligning pin on its pivot when said carrier is rocked in strip aligning direction and operating connections controlled by said operating mechanism to positively swing said carrier in either direction and adapted to complete an align- 35
- ing action of said pins prior to setting said clamp in clamping position.
22. In a strip-aligning device for writing machines, in combination, an oscillatable carrier, means for oscillating said carrier, a strip-aligning pin pivoted to and carried by said carrier and adapted to enter apertures in a strip in effecting strip alignment, and a trip member attached to and mounted upon the aligning device and cooperating to automatically move said aligning pin upon movement of said carrier. 40
23. In a strip-aligning device for writing machines, in combination, an oscillatable carrier, means for oscillating said carrier, a strip-aligning pin pivoted to and carried by said carrier and adapted to enter apertures in a strip in effecting strip alignment, a pin-operating member operatively connected to said pin, and a trip member attached to and mounted upon the aligning device and operatively engaging said pin-operating member to automatically pivotally move said pin upon movement of said carrier. 45
24. In a strip-aligning device for writing machines, in combination, an oscillatable carrier, means for oscillating said carrier, a strip-aligning pin pivoted to and carried by said carrier and adapted to enter apertures in a strip in effecting strip alignment, a pin-operating member operatively connected to said pin, a trip member attached to and mounted upon the aligning device and operatively engaging said pin-operating member to automatically pivotally move said pin upon movement of said carrier, and a stop for limiting the pivotal movement of said pin on said carrier when in strip-aligning position. 50
25. In a strip-aligning device for writing machines, in combination, a pivotally oscillatable carrier, means for oscillating said carrier, a strip-aligning pin pivoted to and carried by said carrier and adapted to enter apertures in a strip in effecting strip alignment, a pin-operating member carried by the pin and having an operating surface angularly spaced from the pin, and a trip loop carried by the aligning device and positioned for operative engagement either with said pin or with said operative surface to rock said pin in opposite directions upon oscillation of said carrier. 55

In testimony whereof I affix my signature.
LOUIS FRED HAGEMANN.
